FRAME AND DOOR

William Jones, Arlington, Mass.

Application June 18, 1930. Serial No. 462,037

7 Claims. (Cl. 189—46)

This invention relates to metal doors and frames therefor adapted to be assembled with walls and other structures of brick work or masonry to cover openings left in such structures or walls. The openings with which such doors are most commonly used are those provided at the base of chimneys for removal of ashes, soot, etc., accumulating at the bottom of the chimney. Doors of this type are also applicable to the ash pit openings and entrance to the fuel spaces of brick furnaces and to a variety of other uses. The specific embodiment chosen for illustration herein is a door and frame of a standard size for use as the clean-out door at the bottom of a chimney, but this illustration is not to be taken as a limitation of the utility and scope of the invention, for the same principles may be applied in doors of any size to be placed in an opening of corresponding dimensions in masonry walls and other structures of any character whatever. The objects of the invention are to provide in a frame, associated with a door of this character, means for effecting a more secure anchorage in the brick work or masonry than has been possible heretofore and to facilitate the building of the wall or structure with the frame in place therein. The particulars of the new features by which these and other related objects are accomplished, are disclosed in the following specification, in connection with the drawing, and particularly recited in the appended claims.

In the drawing,—

Fig. 1 is a front elevation of a section of a brick chimney wall with my improved door frame and door built into it;

Fig. 2 is an elevation of the rear side of the same wall and door frame;

Fig. 3 is a perspective view of the frame and associated door as viewed from the rear and from above;

Fig. 4 is a section on line 4—4 of Fig. 1.

In the drawing, 1 represent the door, 2 the frame, and 3 the wall; the frame and door being coupled together by hinges 4 and 5 of any ordinary or other suitable character and having co-operating hook and hasp members 6 and 7 for holding the door in closed position, these being also of usual or any other suitable character. A handle 8 is provided on the door as usual.

This frame comprises the walls 10, 10 and includes flanges extending on four sides as a facing to overlie the borders of the hole in the masonry wall wherein the frame is set. At the top of the frame is the horizontal flange 11 which is supported and reinforced by the adja-

cent frame members 10, and extends rearwardly.

This flange is located at the top of the opening. It has a purpose and function not served by any corresponding frame structure heretofore made, which is to support the masonry structure above the opening and to anchor the frame in place during the building of the masonry, and thereafter. To serve these purposes the flange 11 has a width, rearwardly from the plane of the facing flanges, at least equal to a major proportion of the width of the individual bricks or blocks of which the masonry structure is built. This in order that bricks, etc., laid upon it in the regular order of building the wall above the opening, will be stably supported and will not tip over or slide off. At opposite ends of the flange 11 are extensions 15 which project beyond the adjacent members 10, and preferably also beyond the outer edges of the facing flanges, sufficiently to overlap the adjacent bricks or blocks 16 and 17 of the wall at each side of the opening.

In the installation of a clean-out door of this character, the wall is built up in the ordinary way with an opening of suitable height and width to receive the members 10 freely, and in any desired location. When the wall has been built up on each side of the opening to the required height, the frame is placed therein with the extensions resting on the bricks or blocks of the topmost course on each side of the opening, and the body of the frame is placed close against the outer side of the wall, overlapping, and extending beyond, the boundaries of the opening, as shown in Fig. 1.

The next course is then laid, and those bricks or blocks which are laid over the opening rest on the flange 11 and are supported thereby. This flange and its lateral extensions are of a thickness approximately equal to, or possibly slightly less than, the thickness of mortar laid between the courses, and if desired, a thin bed of mortar may be laid on the flange to bind the bricks of the next upper course. But these few bricks may be laid without mortar under them if desired, since the mortar between the adjacent bricks and between them and the ones of the next higher course securely hold the few bricks which overlie the top wall of the frame.

The improved frame herein described has the conspicuous advantages that its extensions or lugs 15 give it a stable support in the wall opening until superposed courses have been laid; that such lugs furnish a permanent bond or interlock after the wall has been further built up, whereby all possibility of the frame becoming accidentally dislodged is excluded without necessity of placing

mortar between the frame at the bottom and sides of the opening; and that the flange 11 affords in itself a support for the bricks of the upper courses. In these respects my improvement marks a decided advance over prior practice in respect to doors of this class. Heretofore the door frames used for the clean-out openings of chimneys, fire and ash pit openings of brick furnaces and the like, have had a narrow rear flange or web bounding all four sides of the opening, and have lacked any equivalent of the wide flange 11 and its extensions 15 here shown. It has been necessary then to fill in the space between the frame flanges and the sides of the opening with mortar and 10 prop up the frame or hold it by some temporary fastening until the mortar has set, and to lay a thin board or shingle across the top of the opening to support the bricks over the opening. This practice, in spite of its inconveniences, has 15 been followed generally by workers skilled in the art for years. All difficulties incident thereto are avoided by my invention, and time and labor are saved in setting the frame and building the wall over it, while the frame is more securely anchored 20 at the same time.

Preferably the frame is made of cast iron, as usual with articles of this class, because of the simplicity and low cost of making it of such material by such mode of manufacture. But other 25 suitable materials may be fabricated in other ways to produce the same result within the scope of the invention. Such frames may be made in any proportions and dimensions suited to the uses to which they are put and the dimensions of the 30 bricks or other blocks of which the wall is made. In any case the front to rear width of the flange 11 is at least equal to a major proportion of the corresponding dimension of the bricks, so as to give a stable support for those which are laid upon 35 it. As designed for walls made of common brick, such width is about three inches. While the thickness of this plate and of its extensions may be varied within limits, as previously explained, I prefer that it shall not be great enough 40 to cause appreciable disalignment of the bricks laid upon it from the rest of the course in which such bricks form a part.

What I claim and desire to secure by Letters Patent is:

- 50 1. A frame for application to an opening in a brick wall or the like having a top plate or flange at the rear side of the frame perpendicular to the plane thereof arranged to be in a horizontal plane when the frame is so applied, with extensions at each end of said plate and in the same plane therewith adapted to be confined between contiguous courses of said wall.
- 55 2. A frame for application to an opening in a brick wall or the like having a top plate or flange at the rear side of the frame perpendicular to the plane thereof, with extensions at each end of said plate adapted to be confined between contiguous courses of said wall, said top plate having a front to rear width equal to a major proportion-

60 tion of the width of the bricks or blocks whereof the wall is composed, whereby to support said bricks or blocks over the opening.

65 3. A door frame for insertion into an opening in the masonry wall comprising a frame body having a central opening, lugs at each side for supporting the frame on the masonry at each side of the unfinished opening, facing flanges extending from the boundaries of said opening, and a top, horizontal, rearwardly extending flange having a width equal to a major proportion of the width of the bricks of which the wall is composed, whereby to support the bricks laid across the 70 opening in the wall.

75 4. A door frame for insertion into an opening in the masonry wall comprising a frame body having a central opening, facing flanges extending from the boundaries of said opening, and a top, horizontal, rearwardly extending flange having a width equal to a major proportion of the 80 bricks of which the wall is composed, whereby to support the bricks laid across the opening in the wall, and said frame having horizontally disposed lugs at the rear of said body and at each side of a thickness substantially equal to the 85 normal separation between courses of the wall adapted to be received between such courses and locked in the wall thereby.

90 5. The combination with a brick wall or the like having an opening, of a door frame in such 95 opening having extension or facing flanges overlapping the borders of the opening and a horizontal rearwardly extending flange provided with extensions at each end entering between courses of the wall at the sides of the opening and providing a support for the bricks of that course 100 which extends across the top of the opening.

105 6. The combination with a brick wall or the like having an opening, of a door frame overlapping the borders of such opening and having 110 a rearward horizontal flange provided with extensions at both ends, said extensions overlying the uppermost bricks at opposite sides of the opening and being overlaid by bricks of that course in the wall which bounds the opening at 115 the top, and the flange throughout its length having a width sufficient to support stably the 120 bricks in said course which overlie the opening.

125 7. A cleanout door for chimneys comprising a frame adapted to be placed over the borders of a cleanout opening in a chimney wall, having horizontal lugs at the rear of its opposite upright sides, projecting outwardly in position to rest on courses of brick at the sides of the opening and having a thickness approximating the normal width of separation between contiguous courses, whereby superposed bricks may be laid in a level line on a lug and the lug-supporting course; and the frame having also a horizontal flange projecting rearwardly from its upper side of a 130 width sufficient to support the bricks of the chimney wall above the opening but insufficient to 135 protrude beyond the rear face of such wall.
